UNITED STATES PATENT OFFICE

2,533,128

LOOM FRAME

Robert G. Mallard, New York, N. Y., and Everett H. Ashton, Jersey City, N. J., assignors, by mesne assignments, to Steel and Alloy Tank Company, Newark, N. J., a corporation of New Jersey

Application August 17, 1946, Serial No. 691,237

2 Claims. (Cl. 139—1)

1

The present invention relates generally to cloth weaving looms and, as illustrated herein, relates more particularly to improvements in side frames for such looms.

The side frames of present commercial looms are formed of cast iron in a single web and are provided with bosses which may be drilled to provide bearing seats for the various oscillating and rotating parts of the loom. The side frames also support various loom mechanisms which are bolted or otherwise secured to either one or both of the loom frames. These frames are not entirely satisfactory since it is necessary to extend various shafts from one loom side to the other. The single web, furthermore, has not proved to be satisfactory support for the loom mechanisms mounted thereon.

Modern high speed looms are provided with various oscillating and rotating mechanisms which may be mounted on either one or both of the side frames. The let-off mechanism, for example, which permits rotation of the warp beam to let-off warp at constant tension as the diameter of the warp yarn on the beam decreases, is mounted on the left hand side frame and is secured in position by bolts or other suitable means. The side frames are also provided with seats for bearings for the main shaft, crank shaft and cam shaft of the loom. These shafts necessarily extend entirely across the loom thus necessitating the use of heavy shafts to prevent twisting and bending thereof. These shafts are necessarily so located that it is difficult to utilize efficiently the space between the loom sides for the harness mechanism and limits the diameter of the warp beam.

Cast iron loom frames are also objectionable since they oftentimes warp and twist out of shape after they are cast. This necessitates aging of the frames before they can be machined. It is not possible with cast iron side frames to provide closely spaced bearings for rocker and other shafts which are subjected to intermittent power impulses or loads. Accordingly, all of these shafts are necessarily heavy and increase the weight and vibration in such looms.

One object of the present invention is to provide an improved loom frame which will overcome the objections above referred to. To this end and in accordance with one feature of the invention, a loom side frame is provided with a pair of spaced vertical webs provided with means for positioning and supporting the various loom mechanisms.

Another object of the invention is to provide

2

a loom construction wherein closely spaced bearings for various shafts permit reduction of size and weight of such shafts with consequent reduction of vibration of such parts.

Another object of the invention is to provide an improved loom construction wherein the various loom mechanisms may be mounted in enclosing casings for unit removal and replacement.

A still further object of the invention is to provide an improved loom frame wherein spaced vertical webs are provided with stiffening and bracing members to prevent flexing of the webs during operation of the loom.

A still further object of the invention is to improve generally upon the construction and operation of high speed fly shuttle looms.

With the above and other objects in view, the invention will now be described with particular reference to the accompanying drawings in which:

Fig. 1 is a view in front elevation of a loom to which the present invention is applied, the various loom mechanisms being shown diagrammatically and with the various manual and automatic control mechanisms not shown;

Fig. 2 is a view in left side elevation of the loom shown in Fig. 1;

Fig. 3 is a view similar to Fig. 2 but showing the right hand side of the loom;

Fig. 4 is a detail view of the inner left web of the frame;

Fig. 5 is a front elevation of the left hand loom frame;

Fig. 6 is a sectional view taken on lines VI—VI of Fig. 3 and shows the sword mounted between the webs of the frame;

Fig. 7 is a detail view illustrating the mounting and positioning of the let-off mechanism;

Fig. 8 is a detail view of the bearings for one end of the crank shaft;

Fig. 9 is a detail view of the picker stick operating mechanism; and

Fig. 10 is a view in front elevation of the mechanism shown in Fig. 9.

The present invention is illustrated as embodied in a fly shuttle loom having a warp beam 10, harness 12, a reciprocating lay 14, and a take-up cloth roll 16 mounted between left and right hand side frames 18 and 20. The left hand side frame 18 supports a let-off mechanism 22 and a take-up mechanism 24.

In the following description of the invention, the left hand side of the loom is at the left hand of an operator facing the loom and the front of the loom is to be understood as that portion of the

loom nearest to the operator. For example, the cloth roll 16 is mounted in the forward portion of the loom and the warp beam 10 is mounted at the rear of the loom.

The novel side frames 18 and 20 are identical in shape but are necessarily provided with different shaped openings for receiving the various operating mechanisms. The left-hand side frame 18 comprises two spaced parallel vertical webs 26, 28. These webs are connected by suitable plates which are located in predetermined vertical and horizontal positions as will later be described.

Before proceeding to a detailed description of the novel side frames 18 and 20, the general organization of the present loom and its main operating mechanisms will be described. The double web side frames 18, 20 of the present machine are provided with openings surrounded by pads 34, 36 respectively on which suitable bearings for a crank shaft 38 are secured. The crank shaft 38 is the only operating element between the warp beam 10 and the take-up mechanism 24 which extends across the entire width of the machine. Thus, the space below the shaft 38 and between the warp beam 10 and the take-up cloth roll 16 is clear of any obstructions which would prevent proper positioning of harness operating mechanism. The crank shaft 38 at its right hand end is provided with a clutch assembly 44 and is driven by a belt 46 from a suitable source of power, such as an electric motor 48. The clutch assembly 44 is supported on a suitable bearing 51 mounted in a bracket 50 which is secured to the outer web of the right hand loom frame 20.

A crank 52 is provided adjacent the right hand end of the crank shaft 38 and positioned between the vertical webs 54 and 56 of the side frame 20 as shown in Fig. 8, a similar crank, not shown, is provided adjacent the right hand end of the crank shaft 38 and is positioned between the vertical webs 26 and 28 of the side frame 18. Suitable bearings are supported in openings 58 and 60 of the left hand frame 18 and openings 62 and 64 formed in the right hand frame 20. The crank shaft is thus rigidly supported and flexing of the shaft 38 is reduced to a minimum. The right hand end of the shaft 38 is provided with a spur gear 66 which meshes with a gear 68 fixed to a cam shaft 70 supported in bearings 72 and 74 fixed in openings 76 and 78 in the inner and outer webs 56 and 54, respectively. The cam shaft 70 is connected to suitable harness operating mechanism by suitable spur gears.

The other end of the crank shaft 38 is provided with a spur gear 80 which meshes with a spur gear 82 fixed to a cam shaft 84 journaled in suitable bearings supported in aligned openings in the inner and outer webs 28 and 26 of the left hand side frame 18. The inner end of the shaft 84 has fixed thereto a bevel gear 86 which meshes with and drives a second bevel gear 88 fixed to the rearward end of a horizontal shaft 92. At its forward end, the shaft 92 is connected by a suitable coupling to the take-up mechanism 24 contained within an enclosing casing 96.

The cranks 52 are connected to the swords 110 by suitable connecting rods. The lay 14 carries at each end a suitable shuttle box 102 into and out of which a shuttle 104 is picked during operation of the loom. The shuttle boxes 102 are provided with shuttle checking devices of any suitable construction. The bottom of each shuttle box is slotted to receive the upper end of a picker stick 106 having fixed to its upper end a picker 108 arranged to engage the tip of the shuttle 104.

The lay 14 extends entirely across the loom and is supported adjacent to each end by swords 110 which are pivoted on stub shafts 112 rotatably mounted in suitable bearings 114 and 116 mounted on the inner and outer webs of each of the side frames 18 and 20. Thus, as the crank shaft 38 is rotated during operation of the loom, the lay 14 is reciprocated forwardly and rearwardly of the loom. A reed 118 is carried by upwardly extending projections on each of the swords 110 and acts at the end portion of the forward reciprocation of the lay to beat up the filling carried across the loom by the shuttle 104.

The lower end of each picker stick 106 is fixed to a parallel 120 which rocks on a parallel shoe 122 fixed to the outer end of each stub shaft 112. The lower surface of each of the parallels 120 is provided with a cam surface which is designed to cause the picker 108 on each picker stick 106 to travel in straight line parallel to the bottom of each of said shuttle boxes 102. Each parallel shoe 122 is provided with generally vertical frames 124 which are provided with surfaces arranged to prevent jumping of the picker stick 106 at each end of its rocking movement.

Each picker stick 106 is operated alternately to pick the shuttle 104 across the loom. The cam shaft 70 on the right hand side of the loom has fixed thereto a usual pick cam 126 having a pick toe 127 thereon. The cam 126 operates a bell-crank 128 having a depending arm 131 which is swung in a clock-wise direction in its picking movement. The arm 131 carries thereon a usual lug strap 128 having a looped portion embracing the picker stick 106. Movement of the arm 131 is transmitted through the lug strap 128 to the picker stick 106 which in turn rocks on the parallel shoe 122 and transmits its motion to the shuttle 104. The shuttle is thus thrown across the lay and into the other shuttle box where it is checked by the usual picker and shuttle checking mechanism. A similar pick motion operated from a pick cam, not shown, on the shaft 84 is at the left side of the loom.

The inner web of each side frame 18 and 20 is provided with a downwardly and forwardly curved slot 130 for receiving the end gudgeons of a warp beam shaft 132. The shaft 132 thus seats itself in the forward end of each slot 130 and is locked in such position by any suitable means. The warp beam 10 is provided with suitable beam ends 134, 136 between which the warp threads 138 are wound on the beam. The left hand end 134 of the beam is provided with a gear 139 which meshes with a spur gear 140 of the let-off mechanism 22 which controls the rotation of the warp beam 10 and permits warp to be uniformly let-off therefrom. The let-off mechanism may be of any well-known type but preferably is a so-called uniform tension friction let-off wherein the warp beam 10 rotates to let-off the warp when the tension thereon exceeds a predetermined amount. The let-off friction is controlled by the diameter of the warp to compensate for changes of diameter thereof.

The take-up mechanism 24 as hereinbefore stated is enclosed in the casing 96 to permit ready removal thereof from the loom for repair and replacement.

The present loom is provided with a hopper stand 144 mounted on the right-hand frame 20 and carries a supply of filling bobbins 146 which are automatically inserted into the shuttle 104 to replace a bobbin on which the filling yarn is exhausted. This automatic bobbin changing

mechanism (not shown) may be of the type used in present commercial looms but it is evident that other bobbin supply means could be used if so desired.

The loom is also provided with suitable manual and automatic stopping means but these are not shown herein since they form no part of the present invention. The essential operating mechanisms have been generally described since the construction of the loom frame of the present invention is to provide suitable means for supporting these mechanisms.

The left hand loom frame 18 is provided with means for rigidly supporting the let-off mechanism 22 and the take-up mechanism 24. The enclosing casing 142 for the let-off mechanism is provided with a flange 148 which is seated on a pad 150 welded to and surrounding an opening 152 formed in the outer frame member 26 of the left hand side frame 18. The casing 142 is provided with an inwardly extending boss 154 having a suitable bearing therein in which a projecting shaft 156 is journaled. The boss 154 fits into an opening 158 formed in the inner web 26 and which assists in positioning the spur gear 140 in mesh with the warp beam gear 139. The flange 148 is provided with suitable openings for receiving cap screws 160 threaded into threaded holes in the pad 150. The let-off casing is also provided with a second inwardly extending boss 162 carrying a shaft 164 which extends through an opening 166 in the inner web 28. The inner end of the shaft 164 carries a generally upwardly extending arm, not shown, which engages the warp on the warp beam and controls the operation of the let-off mechanism as is usual in constant tension let-offs. With the construction described just above, the let-off may be removed as a unit and another let-off substituted therefor with a minimum loss of time. The take-up 24 is similarly mounted in the forward portion of the left hand side frame 18. The take-up 24 is mounted in a casing 96 having a flange 170 arranged to seat on a pad welded about the margin of an opening in the outer web 26. The inner web 28 is provided with an opening 176 which receives a projection 178 of the casing and which carries therein bearings in which the rearwardly extending shaft 92 is mounted. The casing 96 is secured in position by suitable cap screws 180. After these cap screws have been inserted the coupling adapted to connect the forward end of the shaft 92 to the take-up mechanism 24 within casing 96 is fixed in position and tightened to provide an operative connection between the shaft 92 and the take-up mechanism 24.

It is to be noted that the side frame 18 is provided with a plurality of vertical and horizontal bracing plates. These plates not only stiffen the frame but prevent any slight bending of the webs at points where substantial strain is applied to the webs.

Referring now particularly to Figs. 4 and 5, the webs 26 and 28 are secured together by top and bottom plates 182 and 184, respectively. The lower spacing plates 184 are located between the webs 26, 28 and are welded in position. The upper spacing plates 182 are seated along spaced portions at the top of the webs and are likewise similarly welded in position. These plates 182, 184 are so positioned that convenient access may be had to parts interposed between the webs 26, 28.

A horizontal reinforcing or bracing plate 186 is fixed in position to support the take-up casing as it is being placed in position and also acts to

take up any bending moments to which the frame 18 may be subjected by reason of the operation of the take-up mechanism 24. A vertical bracing plate 188 is welded between the webs 26, 28 and further reinforces and braces the frame against slight bending or buckling.

The frame 18 is subjected to substantial strain by the let-off mechanism 22 and this is minimized by a horizontal plate 190 welded in position between the webs 26, 28 just above the opening 152 into which the let-off casing 142 is inserted. A substantially vertical plate 192 is positioned just forwardly of the opening 152. The lower plates 184 adjacent to the opening 152 are effective also to stiffen and brace the frame 18. The frame 20 is also provided with similar spacing and bracing plates which are likewise welded in position.

The frames 18, 20 are preferably provided with a plurality of pads surrounding the various openings in the frames. These pads, however, are not essential in all cases since it is evident that bearings could be secured directly to the webs, if so desired. The pads surrounding openings for receiving the take-up and let-off mechanisms, however, are preferably provided since the webs may not be sufficiently thick to be satisfactorily threaded to receive the cap screws.

The outer web 54 of the right hand side frame 20 is provided with an opening 194 for receiving the motor 48. The motor 48 is mounted on a pivoted support 196 which is supported on a horizontal rod 198 fixed to the webs 54, 56. The motor 48 is normally supported by the belts 46 but provision is made to enable these belts to be tightened as may be necessary. A bolt 200 pivoted to the outer web 54 at 202 extends through an opening in the support 196. Nuts 204 are threaded in the portion of the bolt 200 located above the support 196 and when tightened thereagainst serve to increase the tension on the belts 46.

As shown in detail in Fig. 8, the crank shaft 38 is mounted in bearings 206, 208 which are secured to the pads 34, 36, respectively, by bolts 210, 212. Bearings for the other rotating or reciprocating parts of the loom are similarly mounted but are not shown or described in detail since the specific bearings and securing means therefor form no part of the present invention.

It is apparent that the size and location of the openings, spacers, and bracing plates may be varied as desired. It is also evident that pads about the openings may be eliminated, if so desired.

The parts of the present loom frame have been described in detail but it is believed that a clearer understanding of the invention will be gained by summarizing briefly the advantages gained thereby. The elimination of long shafts extending entirely across the loom permits better and more efficient positioning of many of the loom mechanisms and has the further and striking advantage that the dimensions of the loom may be decreased from front to back to maintain a short warp line. This is of substantial importance since it reduces substantially wear on the warp and hence reduces to a large extent stopping of the loom as a result of warp breakage. The decreased depth of the loom is made possible by the absence of interfering mechanisms which have heretofore prevented the warp beam from being mounted nearer the breast beam.

Another important advantage obtained is the elimination of vibration as a result of closely spaced bearings for reciprocating mechanisms

such for example, as the lay, whereby the use of long heavy shafts is avoided. This also permits the use of lighter parts which decreases substantially the inertia of various mechanisms. Vibration is reduced through the use of lighter parts and through the use of better and more closely spaced bearings.

Having thus described our invention, what we claim as new and desire to secure by Letters Patent of the United States is:

1. In a loom, a side frame, said side frame comprising a pair of spaced substantially vertical webs adapted to support operating loom parts, spacing means attached to the edges of said webs uniting said webs into a unitary structure, one of said webs having an opening therein for passage as a unit into the space between said webs of a loom mechanism including one or more elements adapted to operatively connect said mechanism to loom components positioned on the outside of the other web, means adjacent said opening for connecting said mechanism as a unit to said one web, said other web having one or more holes therein permitting passage of said one or more elements therethrough when said mechanism is properly positioned relative to said loom components, said one or more holes serving as positioning means for said mechanism during the installation thereof, and stress distributing members spanning the space between said webs positioned proximate said opening and united to each of said webs to reinforce said webs and acting to distribute the stress loading of said side frame due to loom operation to both of said webs.

20

25

2. In a loom, opposed side frames therefor, each comprising a pair of substantially vertical plate members, connecting means spacing said vertical plate members to form an integral structure, a warp beam mounted between said opposed side frames, let off mechanism for controlling the rotation of said warp beam during the operation of the loom mounted on one of said vertical plate members of one side frame, said one of said

5 vertical plate members having an opening for receiving said let off mechanism, the other plate member of the said one side frame having an opening for positioning said let off mechanism in operating relation relative to said warp beam, 10 said connecting means including plate members adjacent said first named opening to prevent flexing of the said vertical plate members and to distribute between the said vertical plate members the stresses caused by operation of the loom.
